UNITED STATES PATENT OFFICE.

HARMON E. LINDBLADH, OF BOSTON, MASSACHUSETTS, ASSIGNOR TO THE LINDBLADH CORPORATION, A CORPORATION OF MASSACHUSETTS.

RULING-MACHINE.

1,220,351.

Specification of Letters Patent. Patented Mar. 27, 1917.

Application filed March 3, 1913. Serial No. 751,960.

To all whom it may concern:

Be it known that I, HARMON E. LINDBLADH, a citizen of the United States, residing at Boston, in the county of Suffolk and State of Massachusetts, have invented a new and useful Ruling-Machine, of which the following is a specification.

My invention relates to ruling machines, and especially concerns the type in which means are provided for individually controlling the action of the ruling devices. Its purpose is generally to increase the precision of the machine and the ease with which it may be operated.

In the accompanying drawings, in which like characters designate similar parts throughout, Figure 1 is a broken top plan view of one embodiment of the invention; Fig. 2 is a side elevation thereof; Fig. 3 is an enlarged central vertical longitudinal section through a portion of the machine; Fig. 4 is an enlarged detail in front elevation of a part of the gate; Fig. 5 shows an enlarged section on the line A—A of Fig. 1; Fig. 6 is a top plan view of Fig. 5; Fig. 7 illustrates in plan one of the carrier-sleeves for the controlling levers; Fig. 8 is a perspective view of a clip for securing said levers to one another; Fig. 9 shows in side elevation the spring for cushioning the pen-beam and the adjusting means for said spring; Fig. 10 is a detail of the universal support of the pen-beam, and Fig. 11 illustrates a form which may be ruled by a single operation of my improved machine.

Journalized at their opposite extremities in a suitable supporting frame 10 are drums, one appearing at 11 in Fig. 2 of the drawings, over which operates a belt or feeding member 12. This belt passes above a guide-roll 13 rotatable in the frame, and across a table 14 having its upper face lying in a substantially horizontal plane beneath the ruling devices, which are to be later described. Above the belt-drum 11 is journalized in the frame a feed-drum 15, between which and the belt the work or sheets to be operated upon are introduced from a delivery-shelf 16. Power is applied to the feeding members through a main driving shaft 17 carrying a pulley 18 which may be rotated at the desired speed by a belt from a convenient source of power. Fast upon the shaft 17 is a pinion 19 meshing with a gear 20 fixed upon the spindle of the feed-

ing drum 15. This gear co-operates in turn with a gear 21 of the same diameter upon the spindle of the belt-drum 11, thus causing the advance of the belt and the periphery of the feeding drum at the same speed. To allow the driving power to be thrown off the machine, the connection between the shaft 17 and pinion 19 is through a clutch 22 which may be shifted by a rod extending across the machine and having a handle in a convenient position to be grasped by the operator. As it may be desirable in adjusting the machine to temporarily operate it by hand, a crank 23 is secured to the spindle of the drum 15 adjacent to the handle of the clutch-rod.

Supported upon the top of the frame is a base-plate 24, preferably in the form of an open rectangle, from the longitudinally extending side members of which rise opposite standards 25, 25, in which a transverse bar or beam 26 is supported near the rear of the table 14. Upon this bar are mounted pens or ruling devices 27 of any suitable construction they being in the present instance of flexible sheet metal, each having a shank 28 which is grasped by a clamp 29 secured to the beam through set-screws 30. The points of this series of pens co-operate with the belt 12 over the table 14. They are supplied with ink of the desired color by any convenient device (not illustrated).

At the opposite ends of the pen-carrier beam are spindles 32 and 33 carried by frames 34, 34 supported upon the standards 25. To enable the pen-beam to be adjusted vertically with respect to the work passing beneath it upon the belt, the frames are slotted and through these slots and through openings in the standards project bolts 36. These bolts when tightened serve to fix the frames in the desired position upon the standards. To permit horizontal adjustment of the beam laterally of the machine, the spindle 32 is threaded through its frame 34, and has a hand-wheel 37 by which it may be turned. To lock the threaded spindle in position, a handled nut 38 operating upon the spindle may be forced into contact with the frame. The opposite spindle 33 is mounted to slide with some lateral play through an opening in a swiveled turret 30 and to rotate therein. The spindle 32 is connected by swivel 40 to a block 39, preferably movable on a pair of vertical trunnions 140 110

in a frame 35, which is in turn trunnioned on horizontal pivots 31 to the end of the beam to furnish a universal joint (Fig. 10). When it is desired to lift and lock all the 5 pens clear of the belt, the beam is raised by an arm 41 until a screw 42 threaded through a boss thereon and provided with a lock-nut 43 is above a latch 44 pivoted upon a bracket 45 projecting from the frame 34 of the 10 spindle 32. The latch is then turned into the path of the screw, and the bar is thereby held in its upwardly tilted position until it is again released by throwing back the latch.

In this machine I furnish means for independently controlling the engagement with the work of each pen of the series of this beam 26 and for simultaneously moving the entire series as well. Extending across the machine at the rear of the pen-beam 26 is 15 a shaft or like support 46 fixed in standards 47, 47 carried by the base-plate 24. Upon this shaft, arranged in a single series, are fulcrumed lifting or controlling levers 48 each having a nearly horizontal arm 49 projecting beneath the beam 26 to a point near the forward extremities of the pens. The opposite arm of each lever is upwardly inclined, and has a substantially horizontal extremity 50 for contact with the actuating 20 members to be hereinafter described. There may be carried upon the shaft 46 controlling levers for as many of the pens as may be at any time employed, those which it is not desired to actively use being moved to 25 one side out of the path of the sheets traveling through the machine, as is shown in Fig. 1.

Since it is often necessary to operate closely adjacent pens, and as these pens are 30 individually very narrow, the controlling levers must be thin, and consequently themselves present little bearing surface to the shaft 46. Therefore, if they were supported directly upon the shaft, they would tend to 35 rock laterally and become disengaged from the pens. To overcome this difficulty, I preferably mount the levers in groups upon carriers, each group being held against angular lateral movement by such carrier. In the present 40 instance, the levers are illustrated as being carried in pairs upon sleeves 51, the interior of which fit the shaft 46 to slide thereon, while upon the exterior the levers oscillate, contacting with one another at their adjacent 45 faces. At one end of the sleeve is an integral flange 52 against which one of the levers rests, and at the opposite end is a removable flange 53 retaining the associated lever, this flange being secured in place by 50 screws 54 engaging the end of the sleeve. The outer sides of each pair of the levers are provided with annular recesses surrounding the openings through which the sleeve passes, these recesses being of such size as to 55 receive the flanges 52 and 53, their outer

surfaces being practically flush with the faces of the levers. To prevent the rotation of the sleeves 51 upon the shaft 46, the latter has a spline 112 entering grooves along the interior of the sleeves, which are still freely movable across the machine. By this carrier arrangement I am able to place the controlling levers as closely to one another as though they were mounted directly upon the shaft, and yet provide them with positive support against lateral displacement. If it is desired that certain of the controlling levers shall move together as a unit, for example the two levers mounted upon one of the sleeves, 70 a clip 55 may be placed over the ends of the portions 50. This clip is preferably constructed of resilient sheet metal, made in the form of a rectangle with an opening at one side and so flared at 56 that it may be readily placed in engagement with the levers. When 75 the pair of levers is thus connected, they may be moved together under the influence of common actuating means and will then lift adjacent pens together. Obviously the 80 clips may be made of different sizes to embrace different groups of levers. 85

To hold the levers which are in use in correct relation to the pens with which they are to coöperate, the shaft 46 is provided with a series of generally V-shaped grooves 57 (Fig. 6) extending about a portion of the circumference of the shaft and respectively aligned with the pens. Each controlling lever has a projection, preferably furnished by a 90 stud 58 carried by a lever 59 fulcrumed at 95 60 upon the controlling lever. A spring 61, interposed between the end of the lever 59 opposite the stud and the controlling lever, forces the stud through an opening in the 100 controlling lever and through a slot 62 in the sleeve 51. The pointed end of the stud is 105 adapted to enter any one of the grooves in the shaft, according to the place to which the sleeve carrying the lever is moved. When thus positioned it is forced into the 110 groove by its spring, furnishing a latch 115 readily releasable by pressure of the finger of the operator upon the outer end of the lever 59. When in engagement with a 120 groove, this latch holds the controlling levers 115 and their sleeve against displacement along the shaft 46, yet leaves said lever free to oscillate about the shaft. In this movement of oscillation the forward point of the controlling lever rests against the underside of the corresponding pen, and when its opposite end is depressed raises the working point of the pen from the belt, this pen-movement 125 being permitted by the flexibility of its shank.

To maintain each controlling lever normally in contact with its pen, there is secured to said lever a leaf-spring 63 which extends over a rod or bar 64 supported near the top of the standards 47. However the 130

levers may be situated their springs, which are bodily movable with them, will find engagement with this rod and thus always be under tension, irrespective of lateral adjustment.

Fixed to the rod 64 near each extremity within the standards 47 are arms 66 held in place by set-screws 67. At the outer ends of these arms are openings to receive and support a rod or bar 68 engaged by set-screws 69 threaded through the arms. This rod 68 extends over and in close proximity to all the controlling levers and serves as a stop common to them. When the position of the rod is adjusted vertically by loosening the set-screws 67 and swinging the arms about the rod 64, the distance which the pens are allowed to move toward the work by the controlling levers is simultaneously varied for the entire series. This may be useful in connection with operations upon sheets which present irregular or wavy surfaces, since in this manner the clearance of the released pens from the sheets may be assured. To separately align the controlling levers and to properly position their forward extremities with respect to the pens, each lever carries upon its upper edge an adjustable contact member or block 70 lying below the stop-rod 68. The upper face of the block is shown as inclined, so that upon its movement longitudinally of the lever the vertical position of the point of contact between the block and stop-rod will be altered. To shift the block an adjusting member is provided, consisting of a screw 72 threaded through a lug 73 rising from the lever and having a non-threaded end-portion freely rotatable in the block. This end is retained in engagement with the block by a head 74 at one side and a collar 75 at the other. At the forward end of the screw is a thumb-piece by which it may be readily turned by the operator, and any one of the controlling levers thus quickly adjusted with respect to its pen without the use of tools. The screw 72 is held in its adjusted position by lock-nut 76 contacting with the face of the lug 73.

In some work, instead of lifting the pens individually, it may be desired to operate them all simultaneously. In such case it is convenient to rock the beam 26 as a whole upon its swivel 40 and spindle 33. To effect this movement the arm 41 may have a contact surface 77 (Fig. 2), which is engaged by a special controlling lever 78 fulcrumed near one extremity of the shaft 46. A spiral spring 79 (Fig. 3), extending between the base-plate and an arm 80 projecting from the beam near the spindle 33, draws the end of the screw 42 against a portion of the bracket 45. To cushion the downward movement of the relatively heavy beam, the end of the arm 80 contacts with a spring 81, shown as occupying an inclined position and

projecting from a block or carriage 82 mounted to slide in a way 83. This carriage has a slot through which extends a screw 84 to secure it in position, this determining the cushioning effect of the inclined spring. Though differently proportioned to adapt it to the service it is to perform, the lever 78 is in no essential particular different from the levers 48, except that as the former may be of ample width at its fulcrum point on the shaft 46, it is unnecessary to mount it upon a sleeve or carrier.

Sometimes, and especially when a form is to be ruled in which a second group of lines begin and end at corresponding points or upon which certain lines are very closely placed, much labor is saved in setting the machine for its work by having a second beam or pen-carrier 85 which may be oscillated as a whole to simultaneously lift its pens. This beam is mounted in advance of the beam 26 on standards 86 fixed to the base-plate 24 in a manner exactly similar to the arrangement of said beam 26. A controlling lever 87 fulcrumed beside the lever 78 upon the shaft 46 directly operates the beam 85. To cause the ends of the levers 78 and 87 to move more readily over the surfaces of the beam-arms, they may be provided at their contact ends with anti-friction rolls 88.

Journalized to oscillate in standards 89, 89 carried by the base-plate is a vertical series of shafts or supports 90, upon each of which may be variably fixed by set-screws 91 a series of actuating arms 92. These arms on the various shafts are of different lengths, but those on the same shaft are of the same length, having horizontal portions 93 and vertical portions 94 which are respectively parallel with one another upon succeeding shafts. All these vertical portions extend over the ends 50 of the controlling levers and coöperate with slots 95 lying along the upper sides of the ends of the levers, these slots retaining the engaging points of the arms against disengagement. The portions 94 of the levers for each shaft 90 occupy different vertical planes with respect to the other groups and thus clear them, so that all the arms of the various groups may be freely adjusted upon their shafts across the machine without interference with the arms of the associated groups.

To impart to each shaft 90, and consequently to each of its groups of arms 92 and corresponding groups of controlling levers and pens, the pen-controlling movement, there is fixed to each shaft 90 a driving arm 96. This arm is fixed by a set-screw 97 to a rod 98 forming one member of a rectangular fulcrum frame, the other members of which consist of the parallel shaft 90 and a pair of arms 99, 99 secured outside the arms 92. Each driving arm 96 has at its outer or rear

extremity an anti-friction roll 100 contacting with a cam-surface 101 upon a wheel 102, the number of wheels corresponding to the number of different pen-movements. 5 These cam-wheels are fast upon a shaft 103 journaled in standards 104, 104 rising from the base-plate, and are rotated by a pinion 105 meshing with a gear 106 turning upon a stud 107 and also engaging a gear 108 on the 10 spindle of the belt-drum 11. The stud is adjustable in a sector-shaped slot concentric with the shaft of the gear 108 and situated in an arm 109 depending from the underside of the base-plate. The pinion 105 is made 15 readily removable so that by placing upon the shaft 103 pinions of various diameters and correspondingly adjusting the gear 106, the rate of travel of the cams with respect to the feeding members may be varied within 20 suitable limits. The cam-surfaces may be furnished by plates 110, situated in peripheral grooves in the wheels 102 and secured by screws 111 engaging circumferential series of holes about the wheels. By altering the 25 extent and location of the plates 110, the contour of each cam-surface may be varied to properly time the operation of its group of actuating arms, controlling levers and pens. To permit a further adjustment of 30 the throw of the actuating arms and therefore of the lift of the pens, each driving arm 96 is made in sections, there being a substantially vertical portion 113 carried by a short angle-arm which is fixed to its shaft, and a 35 generally horizontal portion 114. These two sections are articulated at 115, the last-named having a downward extension at the extremity of which is a slotted sector 116, through which a bolt 117 is threaded into the 40 vertical portion 113. One very marked utility of this adjustment is that if after having correctly arranged the cams to give the desired time of lift and release to the pens it is found that they do not properly discharge 45 the ink for the particular grade of stock operated upon, the angular position of the portion 114 of the driving arm may be changed. This, without varying the point of application and removal of the pens with respect to 50 the work, will alter the distance through which they move before they contact with the sheet, and therefore the force with which they strike, and thus cause the ink to be initially discharged with greater or less freedom. It will be seen that each fulcrum-frame with its actuating arms 92 and driving arms 96 furnish a multiple-armed lever connecting a driving cam with one of the groups of controlling levers, and that the 55 driving arm and actuating arms are each adjustable over the full width of the machine without interference with the opposite arms of the same lever. As the springs 63 force the arms 50 of the controlling levers against 60 the arms 92 of the actuating levers, they

also force the rolls 100 of the driving arms into coöperation with the cam-surfaces. To limit the movement of the driving arms after they have been released by the cams, I have provided a stop-bar 118 extending at the 70 rear of the portions 113 of the levers, and adjustably mount its ends in slots extending horizontally along brackets 119 carried by the standards 89. To cushion the blow of the driving arms upon the stop-bar, thus reducing the shock and noise, sleeves 120 of resilient material, such as rubber, surround the bar. A sleeve for each driving arm is shown, preferably held in place by its own resiliency, and with these sleeves contact 75 lugs 71 projecting from the portion 113 beyond the upper pivoted section. 80

Mounted outside the arms 99 directly on two of the shafts 90, since it is unnecessary to adjust them laterally of the machine, are 85 actuating levers 121 and 122 for the controlling levers 78, 87 and their beams 26, 85, respectively. In the case of these levers the actuating and driving arms may be made integral. The latter arm, however, is preferably formed in adjustable sections similarly to the levers for actuating the individual pens. The transmission of movement from a driving cam to a distant pen-beam, as 85, through two coöperating levers, as 122, 87, 95 instead of through gearing, as is usual in ruling machines, avoids irregularities in the striking of the pens upon the work which would be introduced by the backlash of the gearing. 100

The machine is equipped with a gate 123, which positions each sheet upon the feed-belt and automatically releases it for presentation to the pens. This gate consists of a shaft or support 124 mounted in bearings 125, 125 formed in the cam-shaft standards 104, and has fixed at intervals along it holders 126. In these holders are upwardly extending sockets or openings to receive teeth 127 each secured by set-screws 128. The 105 gates are of considerable length and therefore tend to spring or bend in use, distorting the horizontal line at which the teeth contact with the feed-belt, but with my improved gate each tooth may be independently adjusted by loosening its set-screws, shifting the tooth in its opening, and again turning the screws into engagement with the tooth, thus producing a perfect alinement of the contact portion of the gate. 110 From the shaft of the gate an arm 129 projects into coöperation with a cam 130 carried by the shaft 103. An anti-friction roll 131 upon the gate-arm is shown as drawn into contact with the cam by a spiral spring 132, extending between a downwardly projecting arm 133 and the frame. The working contour of the cam 130 is such that the gate is 115 for a brief period held in the path of an approaching sheet to position it upon the 120 125 130

belt, and is then released at the correct time with respect to the cam wheels 102 to free said sheet and allow it to travel with the belt beneath the pens in accord with their lift.

5 The sheets to be operated upon may be so cut that their adjacent edges are not truly at right angles, and to present the sheets properly it may be necessary to adjust the angle of the gate with relation to the feed-belt to cause the ruled lines to become parallel with the edges of the sheets which extend in the direction of said lines. To effect this, the base-plate 24 is movable upon the top of the frame, being pivoted at one corner upon a screw 134, and clamped in place by a screw 135 passing through a slot 136 (Fig. 1) in the base-plate into engagement with the frame. When it is desired to vary the position of the gate to correspond to the 10 previously mentioned irregularity of the sheets, the screws 134 and 135 are loosened and the base-plate swung about the former through an angle corresponding to the departure of the edges of the sheet from a 15 right angle, the slot 136 permitting this movement. Then both screws are again turned down to fix the plate in position. In thus positioning the gate both pen-beams and all the controlling elements are shifted 20 to the same extent, so that the lift of the pens is not altered. I also prefer to provide for the independent adjustment of all the standards upon the base-plate, and to this end each of the standards 47, 89 and 104 has 25 in its foot slots 137 lying longitudinally of the frame, through which slots pass screws 138 into threaded openings in the base-plate. The beam-standards 25 move in ways 139 in which they are secured by screws 141. By 30 this means the position of the pen-bars, controlling and actuating levers, and cams and gate may be very precisely fixed with respect to one another and to the feed-belt.

To prepare this ruling machine to produce, for example, the form illustrated in Fig. 11, a controlling lever 48 is adjusted beneath each pen which is to be separately raised from the work. This is accomplished by sliding the sleeve 51 carrying the levers 49 along the shaft 46, the spring latch of the controlling lever being raised, and then releasing this latch to allow the stud 58 to engage in the shaft a groove 57 which is aligned with the pen. When all the pens of 50 the beam 26 are to be lifted at the same time, the lever 78 is brought into action; and for the production of closely placed lines or for other exigencies which the operator may encounter in particular cases, the beam 85 and its lever 87 are employed. For each group of lines beginning and terminating at the same point, other than the two groups corresponding to the movements of the pens of beams 26 and 85 as a whole, a cam-wheel 102, 55 shaft 90 and driving arm 96 are utilized,

with the actuating arms 92 of each shaft corresponding in number to the lines in each group. The number of actuating arms may, however, be modified by the use of the clips 55. The variable cam-plates are adjusted to 70 lift the pens through the lever system at the correct times, the precise contour of these cams not appearing in the drawings. The machine having been set, sheets to be ruled are placed upon the delivery-shelf and successively advanced between the belt and the feed-drum. Upon reaching the gate they contact with its teeth and are squared on the belt by them, and then released by the action of the gate-cam at the proper time for presentation to the pens. This time of release bears a definite relation to the period of operation of the pen and beam-controlling cams, so that the beginning of the ruled lines will be at the proper distance from the forward edge of the sheet. As the sheets advance over the table beneath the pens those not lifted by the controlling levers produce their lines; and as the travel of the sheets continues the passing of the cam-surfaces 101 75 from beneath certain of the driving arms drop their pens, which also produce other lines. Thus the ruling of all of the lines running in this direction across the sheet is completed at a single operation, this continuing for each sheet delivered by the gate, the different lengths of lines being automatically controlled throughout. When another form is to be ruled, it is a comparatively simple matter to vary the pens, the actuating 80 and controlling levers and their operating cams to meet the new conditions. 85

While I have herein disclosed a single embodiment of my invention, it is to be understood that it is but one of many which might 90 be employed and still be within the scope of the following claims:

1. In a ruling machine, a plurality of carriers, ruling devices mounted upon the carriers, means individual to the ruling devices 110 of one carrier for moving them from their ruling position, and means for independently moving a plurality of the carriers to simultaneously lift all the ruling devices mounted upon them. 115

2. In a ruling machine, a plurality of beams, ruling devices mounted upon the beams, means individual to the ruling devices of one beam for moving them from their ruling position, and means for independently moving another of the beams to simultaneously lift all the ruling devices mounted upon it. 120

3. The combination with a plurality of pen-beams, of ruling pens carried thereby, 125 a series of lifting members coöoperating with the pens and with the pen-beams, said series of lifting members including one for each pen-beam, and means for oscillating the lifting members. 130

4. The combination with a plurality of pen-beams, of ruling pens carried thereby, a series of controlling members coöperating with the pens and with the pen-beams, means for oscillating the pen-controlling members in groups, and means for oscillating the beam-controlling members individually.
5. The combination with a plurality of pen-beams, of ruling pens carried thereby, a support, controlling levers, mounted on the support, there being a lever for coöperation with each pen-beam and levers for coöperation with certain of the pens, and means for actuating the levers.
- 10 6. The combination with a plurality of pen-beams, of ruling pens carried thereby, a support, lifting levers mounted on the support, there being a lever for coöperation with each pen-beam and levers for coöperation with certain of the pens, the pen-levers being located at intervals along the support and the beam-levers being situated near one extremity of the support, and means for actuating the levers.
- 15 7. The combination with a plurality of pen-beams, of ruling pens carried thereby, a support, controlling levers mounted on the support, there being a lever for coöperation with each pen-beam and levers for coöperation with certain of the pens, actuating levers for the controlling levers, a cam for each beam-actuating lever, and cams for operating the pen-actuating levers in groups.
- 20 8. In a ruling machine, the combination with ruling devices, of controlling members therefor, a support upon which the controlling members oscillate, and means limiting the movement of said members in their oscillation for varying the extent of said oscillation.
- 25 9. In a ruling machine, the combination with a ruling device, of a controlling member movable into coöperation with said ruling device, a stop for the controlling member, and a movable contact member for varying the coöperation between the stop and controlling member.
- 30 10. In a ruling machine, the combination with a ruling device, of a controlling member mounted independently of said ruling device, a stop for the controlling member, and a movable contact member carried by the controlling member between the stop and the controlling member.
- 35 11. The combination with a ruling pen and a lifting lever therefor, of a stop for the lifting lever, a contact member carried by the lifting lever, and a screw threaded into the lifting lever and engaging the contact member.
- 40 12. The combination with a ruling pen and a lifting lever therefor, of a stop for the lifting lever, a block carried by the lever and having an inclined face for contact with the stop, and means for varying the position of the block upon the lever.
- 45 13. In a ruling machine, the combination with ruling devices, of controlling levers therefor, a stop common to all the controlling levers, means for varying the position of the stop, and means individual to the levers for varying the points of contact between said levers and the stop.
- 50 14. The combination with ruling pens and lifting members therefor, of means including an element common to a plurality of the lifting means and elements individual to said lifting means for separately varying the downward movement of the lifting means.
- 55 15. In a ruling machine, pens, controlling members therefor, a stop with which the controlling members contact, supports upon which the stop is mounted, a rod about which the supports are movable, and springs for the controlling members coöperating with the rod.
- 60 16. In a ruling machine, pens, controlling members therefor, a bar with which the controlling members contact, arms upon which the bar is mounted, a rod about which the arms are movable, and springs secured to the controlling members and contacting with the rod.
- 65 17. The combination with ruling pens, of a controlling lever therefor, a support for the lever provided with grooves, a movable projection carried by said lever, and a spring for forcing the projection into the grooves.
- 70 18. The combination with ruling pens, of a controlling lever therefor, a support for the lever provided with grooves, and a latch movable on the controlling lever and having a projection for engagement with the grooves.
- 75 19. The combination with ruling pens, of a controlling lever therefor, a support for the lever provided with grooves, a latch movable on the controlling lever and having a projection for engagement with the grooves, and a spring cooperating with the lever and latch.
- 80 20. A ruling machine comprising ruling devices, a support, a carrier movable upon the support, and a plurality of controlling members for the ruling devices mounted to oscillate upon the carrier.
- 85 21. A ruling machine comprising ruling devices, a support, a carrier movable upon the support, and a plurality of controlling members for the ruling devices mounted to oscillate upon the carrier, the adjacent controlling members moving in contact with one another on the carrier.
- 90 22. A ruling machine comprising ruling devices, a support, a carrier movable upon the support, and a plurality of controlling members for the ruling devices mounted to

- oscillate upon the carrier, the adjacent controlling members moving in contact with one another on the carrier and the outer members contacting at their sides with the carrier. 5
23. Ruling pens, a shaft, a sleeve movable on the shaft, and controlling levers for the pens fulcrumed on the sleeve and having means for engaging the shaft. 10
24. Ruling pens, a shaft, a sleeve on the shaft, and a plurality of lifting levers fulcrumed in contact with one another upon the sleeve and providing mutual lateral support. 15
25. Ruling pens, a shaft, a flanged sleeve on the shaft, and controlling levers for the pens fulcrumed on the sleeve, the sleeve flanges providing lateral support for the levers and said levers also offering mutual support. 20
26. Ruling pens, a shaft, a sleeve movable on the shaft, and controlling levers for the pens fulcrumed on the sleeve, there being flanges at the extremities of the sleeve for retaining the levers thereon, one of said flanges being separably secured to the sleeve. 25
27. Ruling pens, a shaft, a sleeve movable on the shaft, and controlling levers for the pens fulcrumed on the sleeve and having recesses, there being flanges upon the sleeve lying within the recesses. 30
28. Ruling pens, a shaft provided with grooves, a sleeve surrounding the shaft and having an opening, and a pen-controlling lever carried by the sleeve and having a projection extending through the opening for engagement with a groove. 35
29. Ruling pens, a shaft provided with grooves, a sleeve surrounding the shaft and having a slot, and a pen-controlling lever mounted to oscillate about the sleeve and having a projection extending through the slot for engagement with the groove. 40
30. A ruling machine comprising ruling devices, a support, a carrier movable upon the support, a plurality of controlling members for the ruling devices mounted to oscillate upon the carrier, and means for securing the controlling members to move together upon the carrier. 45
31. In a ruling machine, ruling pens, lifting levers therefor, and a spring clip adapted to secure adjacent levers to move together. 50
32. In a ruling machine, ruling devices, a lever having oppositely extending arms and separate supports upon which each arm is movable independently of the opposite arm, and means by which the lever operates the ruling devices. 55
33. In a ruling machine, ruling pens, a lever consisting of parallel rods and an arm secured to each rod, and means by which the lever operates the ruling devices. 60
34. In a ruling machine, ruling pens, a lever consisting of rods and an arm secured to each rod, one of said rods serving as a fulcrum for the lever, and means by which the lever operates the ruling devices. 65
35. The combination with ruling pens, of a series of controlling levers therefor, a series of cams, and an actuating lever connecting the controlling levers and cams, said actuating lever being provided with a cam-engaging arm and a controlling lever engaging arm, each arm having a support individual to it and permitting movement of the arm into coöperation with the entire series of cams, to be engaged independently of the movement of the associated arm. 70
- 75
36. The combination with ruling pens, of a series of controlling levers therefor, a series of cams, and an actuating lever connecting the controlling levers and cams and consisting of a fulcrum-frame having adjacent members extending along the entire series of cams and controlling elements and arms adjustably mounted on the frame members. 80
- 85
37. A ruling machine comprising ruling devices, means for moving the ruling devices, lifting levers for the ruling devices, and a lever interposed between said moving means and the lifting levers and having an arm formed in pivoted sections, with means for securing said sections at different angles to one another. 90
- 95
38. A ruling machine comprising pens, controlling levers therefor, a cam, and a lever having an arm for engagement with the controlling levers and an arm for engagement with the cams, the latter arm being provided with a portion movable to vary the travel imparted to the lever by the cam. 100
- 105
39. A ruling machine comprising pens, a cam, a lever interposed between the pens and cam, a stop-bar for the lever when released by the cam, and a resilient sleeve surrounding the bar and with which the lever contacts. 110
- 115
40. In a ruling machine, a frame, means for moving work thereover, a base-plate supported upon the frame, means for attaching the base-plate to the frame to swing thereon, means for fixing the base-plate in the desired angular position, and a gate, ruling devices and controlling means for the ruling devices carried by the base-plate. 120
- 125
41. In a ruling machine, a frame, means for moving work thereover, a base-plate supported upon the frame, means for attaching the base-plate to the frame to swing thereon, means for fixing the base-plate in the desired angular position, a gate, ruling devices and controlling means for the ruling devices carried by the base-plate, and means for variably positioning the gate, ruling devices and controlling means upon the base-plate. 130

42. In a ruling machine, a frame, means for moving work along the frame, a generally rectangular base-plate supported upon the frame, a pivotal connection for the base-plate to the frame near one corner of said base-plate, means for fixing the base-plate to the frame, and a gate, ruling devices and controlling means for the ruling devices carried by the base plate.
- 5 43. The combination with a plurality of ruling devices, of driving means therefor, the ruling devices being situated at different dis-

tances from the driving means, and a plurality of coöperating levers for connecting the driving means and the more distant ruling devices. 15

Signed at Boston, in the county of Suffolk and State of Massachusetts, this first day of March, 1913.

HARMON E. LINDBLADH.
